(57) **CLAIM**

The ornamental design for a sofa and table set as shown and described.

DESCRIPTION

FIG. 1 is a perspective view of a sofa and table set in a combined state, showing my new design;

FIG. 2 is a front, right, top perspective view of the first piece of the sofa and table set, showing my new design;

FIG. 3 is a rear, left, bottom perspective view thereof;

FIG. 4 is a front, right, top perspective view of an enlarged scale thereof in another angle;

FIG. 5 is a front elevational view of an enlarged scale thereof;

FIG. 6 is a rear elevational view of the enlarged scale thereof;

FIG. 7 is a left side view of the enlarged scale thereof;

FIG. 8 is a right side view of the enlarged scale thereof;

FIG. 9 is a top plan view of the enlarged scale thereof;

FIG. 10 is a bottom plan view of the enlarged scale thereof;

FIG. 11 is a front, right, top perspective view of the second piece of the sofa and table set, showing my new design;

FIG. 12 is a rear, left, bottom perspective view thereof;

FIG. 13 is a front, right, top perspective view of an enlarged scale thereof in another angle;

FIG. 14 is a front elevational view of the enlarged scale thereof;

FIG. 15 is a rear elevational view of the enlarged scale thereof;

FIG. 16 is a left side view of the enlarged scale thereof;

FIG. 17 is a right side view of the enlarged scale thereof;

FIG. 18 is a top plan view of the enlarged scale thereof;

FIG. 19 is a bottom plan view of the enlarged scale thereof;

FIG. 20 is a front, right, top perspective view of the third piece of the sofa and table set, showing my new design;

FIG. 21 is a rear, left, bottom perspective view thereof;

FIG. 22 is a front elevational view of the enlarged scale thereof;

FIG. 23 is a rear elevational view of the enlarged scale thereof;

FIG. 24 is a left side view of the enlarged scale thereof;

FIG. 25 is a right side view of the enlarged scale thereof;

(Continued)

FIG. 26 is a top plan view of the enlarged scale thereof; FIG. 27 is a bottom plan view of the enlarged scale thereof; FIG. 28 is a front, right, top perspective view of the fourth piece of the sofa and table set, showing my new design; FIG. 29 is a rear, left, bottom perspective view thereof; FIG. 30 is a front elevational view of the enlarged scale thereof; FIG. 31 is a rear elevational view of the enlarged scale thereof; FIG. 32 is a left side view of the enlarged scale thereof; FIG. 33 is a right side view of the enlarged scale thereof; FIG. 34 is a top plan view of the enlarged scale thereof; FIG. 35 is a bottom plan view of the enlarged scale thereof; FIG. 36 is an enlarged view of detail 36 in FIG. 4; FIG. 37 is an enlarged view of detail 37 in FIG. 9; FIG. 38 is an enlarged view of detail 38 in FIG. 13; FIG. 39 is an enlarged view of detail 39 in FIG. 18; FIG. 40 is an enlarged view of detail 40 in FIG. 20; FIG. 41 is an enlarged view of detail 41 in FIG. 21; FIG. 42 is an enlarged view of detail 42 in FIG. 28; FIG. 43 is an enlarged view of detail 43 in FIG. 29; and, FIG. 44 is an enlarged view of detail 44 in FIG. 34. The dash-dot-dash broken lines are for notating enlarged views and form no part of the claimed design.
